United States Patent Office

Des. 210,797
Patented Apr. 16, 1968

210,797

SELF-STANDING TABLE LAMP

Dennis L. Jones, Coral Gables, Fla., assignor to Meyers Products, Inc., Cleveland, Ohio, a corporation of Ohio

Filed Sept. 26, 1967, Ser. No. 8,746

Term of patent 14 years

(Cl. D48—20)

FIG. 1

FIG. 2

FIGURE 1 is a side elevation of a self-standing table lamp embodying my inventive design; and

FIGURE 2 is a top plan view thereof.

I claim:

The ornamental design for a self-standing table lamp, substantially as shown and described.

References Cited

UNITED STATES PATENTS

D. 181,554 11/1957 Stiffel ----- D48—20
D. 186,547 11/1959 Burton ----- D48—31

OTHER REFERENCES

Lightolier Catalog, rec'd Apr. 21, 1953, p. 9, 9835
lamp at center of page. (Copy in Table Lamp Box A-17.)
Lamp Journal, July 1960, p. 54, pole lamp at lower right of page. (Copy in Floor Lamp Box A-24.)

WALLACE R. BURKE, Primary Examiner.

WILLIAM C. WATSON, Assistant Examiner.